UNITED STATES PATENT OFFICE

92,936

DESIGN FOR A CAP

Henry I. Tobin, Philadelphia, Pa., assignor to
John B. Stetson Company, Philadelphia, Pa.,
a corporation of Pennsylvania

Application April 26, 1934, Serial No. 51,530

Term of patent 7 years

To all whom it may concern:

Be it known that I, HENRY I. TOBIN, a citizen of the United States of America, residing in Philadelphia, county of Philadelphia, State of Pennsylvania, have invented a new, original, and ornamental Design for a Cap, of which the following is a specification, reference being had to the accompanying drawing, forming part thereof.

Figure 1 is a top plan view of the cap.

Figure 2 is a side elevation.

Figure 3 is a front view.

Referring to the drawing, the dominating features of the design are the pronounced oval shape

of the cap, the long axis of the oval being disposed in a fore and aft direction and the V shaped centerpiece which extends the entire length of the cap from the front to the back, the vertex being at the front and the maximum width at the rear, the cap as a whole having a stream line effect.

I claim:

The ornamental design for a cap as shown and described.

Signed by me at Philadelphia, Pennsylvania,
this 23rd day of April 1934.

HENRY I. TOBIN.
